His Attorney

UNITED STATES PATENT OFFICE

2,418,277

ARTICLE WRAPPING MACHINE

Charles H. Petskeyes, Davenport, Iowa, assignor
to Gellman Manufacturing Company, Rock
Island, Ill., a corporation of Illinois

Application June 9, 1945, Serial No. 598,468

2 Claims. (Cl. 93—2)

1

This invention relates to an article wrapping machine. More particularly the invention relates to the provision in a wrapping machine for holding certain folds of the wrapping for the article in place until the final fold has been accomplished.

In this aspect of the invention, it is the object to accomplish this result by an arrangement which will be highly efficient in use and economical in manufacture.

In bread wrapping machines such as those disclosed in United States Patents Nos. 2,276,590; 2,252,028; 2,235,503; 2,232,558 and 2,230,797, the loaves of bread are generally elevated from a lower runway to an upper runway and during this elevation the loaves of bread are subjected to wrapping operation. As the loaves of bread are passed partially wrapped from the elevator to the upper runway, it has been found that the loaves in the wrapper thus completed, have a tendency to unfold during the movement of the bread or other article from the elevator to the upper runway, and especially is this true when the article being wrapped is of a relatively short height.

It is therefore an object of this invention to provide an attachment for article wrapping machines such as disclosed in the aforesaid patents, which will serve to hold the folds in place pending the complete wrapping operation.

Another object of the invention is to provide an arrangement for the above accomplishment, which may be optionally used, that is, if it be found that the article is of such size as does not require the provision of means for holding the folds in place pending the final wrapping operation, the provision for so doing may be temporarily dispensed with or entirely removed.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention illustrating one form of construction;

Fig. 2 is a perspective view of an article partially wrapped;

Fig. 3 is a perspective view of the invention illustrating a slightly modified form of construction.

The drawings illustrate the preferred form of construction by which the several objects of this invention are accomplished.

2

In the drawings, attention is particularly directed to Figs. 1 and 2 showing one form of construction for accomplishing the several objects of this invention.

In this connection the article wrapping machines as shown and described in the patents hereinbefore mentioned include a plate 10 upon which the article is moved, in a manner disclosed in such patents, from an elevator plate 11, which elevator plate has previously received the article to be wrapped from a lower runway (not shown). This plate 10 comprises, at opposite ends, folding plates 12, the plates 12 each having an arcuate slot 13 formed therein and functioning, when the unfolded portions 14 of the article 15 are received in the slots, to fold these portions against the ends 16 of the article 15.

The object, as before stated, of this present invention, is to provide a simple and effective means for holding the folded portions 17 of the wrapper 18 of the article in place pending the movement of the article 15, in a manner disclosed in the aforesaid patents, to the plate 10. To accomplish this, I provide oppositely disposed plates 19. These plates 19, as are the plates 12, are provided with outwardly turned flanges 20 by which the plates 19, and 12, are secured in any suitable manner to the frame of the bread slicing machine (not shown), there being provided suitable openings 21 for the passage of a suitable element (not shown) by which the plates 12 and 19 are connected to the frame of the bread slicing machine.

As shown, the end portions 21 of the plates 19 are substantially spaced from the end portions 22 of the plates 12. With the provision of such a space between these plates, it invariably happens that the folds of the unfinished wrapped loaves of bread or other articles, become loose and turn into these spaces during the movement of the unfinished wrapped loaf of bread from the elevator to the plate 10. To prevent this, I associate with the plates 19, retaining fingers 23 each in the form of an elongated plate of proper width and adjustable relative to the plates 19 and spaced from the plates for passage between the fingers 23 and the plates 19 of the final fold 14 of the wrapper for the article 15. These fingers 23 each carry slotted bars 24 through the slots of which project the stud shafts 25 carried by the plates 19. These slotted bars 24 are retained in an adjusted position by washer elements 26 carried by the stud shafts 25 and frictionally engaging the slotted bars 24 through the medium of spring elements 27. The tension of these spring elements

27 is varied by means of nut elements 28 threaded upon the stud shafts 25.

As shown in Fig. 1, I provide on each of the fingers 23 a vertical handle 29 and a horizontal handle 30 by which the operator of the machine may adjust the slotted bars 24 relative to the plates 19 so as to move the retaining fingers 23 in proper position in the spaces between the plates 12 and 19 so as to function efficiently to retain the folds of the partially wrapped loaf of bread or article 15 as it is moved from the elevator 11 to the platform 10. To complete the invention, each of the plates 19 is provided along the lower edge portion thereof with laterally extended flanges 11' which rest upon adjacent portions of the elevator 11.

In Fig. 2 I have illustrated a modified form of construction. In this form of construction the retaining fingers 23' are pivotally carried by mounting brackets 31 secured as at 32 to the plates 19. Each of these mounting brackets includes a spring detent 33 by which the fingers 23' are retained in proper position in the space between the adjacent ends of the plates 19 and 12. In this form of construction, when it is not desired or not required to use the retaining fingers 23', they are pivoted outwardly away from alignment with the plates 12 and 19. In this form of construction the parts which are a counterpart of those illustrated in the form of construction shown in Fig. 1, are indicated by similar reference numerals.

By the provision of these retaining fingers, the unfolding of the folds of the partially wrapped loaf of bread or other article is prevented, the folds being firmly held in place during the movement of the loaf of bread or other article 11 to the plate 10.

While I have illustrated and described the preferred form of construction for carrying my invention into effect, this is capable of variation and modification without departing from the spirit of the invention. I, therefore, do not wish to be limited to the precise details of construction set forth, but desire to avail myself of such

variations and modifications as come within the scope of the appended claims.

Having thus described my invention, what I claim as new and desire to protect by Letters 5 Patent is:

1. A wrapping machine comprising a pair of spaced parallelly arranged fold plates from between which a partially wrapped article is adapted to be moved, a bottom plate, final fold plates 10 providing together with the bottom plate a channel into which said partially wrapped article is adapted to be received from between said parallel plates for final wrapping, the final fold plates being arranged in spaced parallel relation with 15 respect to each other and in alignment with the parallel plates with confronting end portions of the final fold plates and said parallel plates being arranged in spaced relation with respect to each other, retaining means carried by said parallel plates and disposed in the space between the parallel plates and said final fold plates and adapted to retain the folds of said partially wrapped article in folded position as said article is moved from between said parallel plates into 20 said channel between said final fold plates, said retaining means being spaced from the bottom plate to permit the passage between said retaining means and said bottom plate of the final fold portion of the partially wrapped article.
2. A device substantially as described in claim 1, which device is characterized as having means for connecting said retaining means to said parallel plates for longitudinal adjustment with respect to said plates.

35 CHARLES H. PETSKEYES.
